UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

INSOLE-HEEL-SEAT-TRIMMING MACHINE.

Application filed December 13, 1918. Serial No. 266,589.

To all whom it may concern:

Be it known that I, THOMAS LUND, a citizen of the United States, residing at Beverly, in the county of Essex and State of Massachusetts, have invented certain Improvements in Insole-Heel-Seat-Trimming Machines, of which the following description, in connection with the accompanying drawings, is a specification, like reference 10 characters on the drawings indicating like parts in the several figures.

This invention relates to that class of shoe machinery commonly called "sole edge trimmers." The accompanying drawings show 15 one embodiment of the invention particularly designed to trim the edge of an insole around the heel seat portion, for which purpose the invention has features that are especially adapted to meet the conditions that 20 prevail when trimming an insole on a last prior to assembling a shoe upper therewith. The invention is not, however, limited to this special use, because it includes features that will be found advantageous in trimming 25 soles other than insoles, and in trimming portions other than the heel seat portion.

In the manufacture of welt shoes it has been the practice heretofore to attach an insole temporarily to a last with the toe end 30 of the insole even with the toe end of the last, and when, as often happens, the insole is longer than the last, to trim the excess material of the sole around the edge of the heel seat portion. With a view to facilitating and improving this practice in particular, the present invention has been embodied in a machine adapted to trim the heel seat portion of an insole more or less closely to the contour of the last, and comprising 35 40 improvements in construction that improve the operation.

One important feature of the invention consists in a rotary knife having a circular cutting edge which is moved in the direction of its length to execute a drawing cut. One advantage of a drawing cut is that it minimizes the degree of force necessary to feed the work which, in machines for this purpose, is usually accomplished manually. 45 50 Another advantage of such a cut is that it avoids tearing the sole even though the cutting edge be considerably dulled by wear. This permits longer periods of service between sharpening operations and insures

smooth cutting, particularly at the edges of the sole.

The knife may, and ordinarily would, remain in the work from beginning to end of an operation, and for this reason it steadies the work and, to some extent, guides the latter. This form of knife, therefore, possesses characteristics especially fitting it for use in a machine for trimming the edges of soles generally. For trimming the heel seat of an insole it has a special advantage in 65 that it can not form abrupt shoulders or corners on the edge of the sole where the trimming begins and ends. This objection arises frequently in machines that employ a trimming cutter of the type that executes 70 successive chopping cuts each complete and independent of the others. Various devices have been made to prevent the formation of such shoulders because frequently they are so prominent as to form lumps at the sides 75 of the upper of the finished shoe. This problem is more fully set forth, for example, in Letters Patent of the United States No. 1,311,197, granted July 29, 1919, on application of H. D. Webb.

A gage is provided to hold the last out of contact with the trimming knife, and it is provided with a tongue arranged to extend between the margin of the sole and the last to sustain the margin out of contact with 80 the last and in the most desirable relation to the knife. This gage is preferably mounted so as to be adjustable to locate the line of cut more or less closely to the edge of the last.

Another important object of the invention 90 is to sustain the margin of the sole against the cutting stress of the knife without, however, offering any considerable frictional resistance to the feeding of the work relatively to the knife. For this purpose the invention 95 includes a sole-rest arranged to engage the bottom face of the sole, the main body of the rest being fixed, but being supplemented by an anti-friction member arranged to have rolling contact with the sole to minimize the 100 friction between the sole and the sole-rest. This anti-friction member would preferably be mounted in such manner as to enable it to yield so that the sole may not lose too much of the benefit of the fixed element of 105 the sole rest. In consequence of providing the anti-friction member as a part of the sole-rest, the sole is held against the last

with sufficient pressure to prevent the sole from slipping edgewise relatively to the last, and for this reason the tack that has heretofore been necessary to fasten the heel seat 5 portion of the sole temporarily to the heel seat portion of the last may be omitted. When the anti-friction member is in use the friction between the sole and the sole-rest is so slight in comparison to that between 10 the sole and the last that the sole follows the last instead of slipping relatively thereto.

The sole-rest and the tongue of the gage hereinbefore mentioned form, conjointly, a channel to receive and guide the margin of 15 the sole, and the sole-rest is preferably mounted so as to be adjustable toward and from the tongue to vary the width of the channel according to the thickness of the sole.

20 For some purposes, as in the case of an insole, it is desirable to bevel the edge of the sole rather than to cut it squarely. For this purpose the sole-rest is arranged to present a flat sole-sustaining surface of considerable

25 area, and said surface is arranged relatively to the knife to insure a beveled cut when the bottom face of the sole is seated thereon.

According to the embodiment illustrated the trimming knife is of annular form as distinguished from disk form, and the plane of 30 the sole-rest is tangential to a circle concentric to, but of less diameter than, the cutting edge, in order to produce the beveled cut above mentioned.

35 The invention includes, in addition to the foregoing features, other details of construction and combinations of parts as more fully set forth in the following description, and particularly pointed out in the claims.

40 In the accompanying drawings, which illustrate one embodiment of the invention,—

Fig. 1 is a view in side elevation of a machine embodying the present invention;

45 Fig. 2 is a sectional plan view, on the line 2—2, Fig. 1, showing the parts on a somewhat enlarged scale; and

Fig. 3 is a perspective view of the knife, gage, and sole-rest, on a larger scale.

50 The machine base 1 supports a bracket 2, which carries bearings for a shaft 4 upon which is mounted a knife 6, which is herein illustrated as being hollow or cup-shaped having the general form of a truncated cone 55 and being provided at its base with a continuous annular and preferably sinuous cutting edge 7. A belt 8 passes over idlers such as that indicated at 10, and is driven to rotate the knife shaft 4 through the medium 60 of a pulley 12 on the latter. An arrow in Figure 2 indicates the preferred direction of rotation, although the latter may be reversed if the available driving facilities are such that the reverse direction would be 65 more convenient.

The bracket 2 is provided in its upper face with a groove 14 which receives a guiding rib or projection from a slide 16, and a suitable clamping bolt 18 is provided for securing the slide 16 in different positions 70 along the guideway. The slide carries a gage 5 which is curved substantially in accordance with the cutting edge of the knife, and is arranged to engage the side of the last closely adjacent to the cutting point 75 of the knife when the last is positioned as shown in Figure 2. The function of the gage 5 is to determine how far, if at all, the insole shall project beyond the edge of the heel seat of the last after the excess material 80 has been trimmed, and it does this by holding the last more or less distant from the knife. The gage 5 is provided with a tongue 9 which extends between the bottom of the last and the projecting edge portion of the 85 insole 15 so as to position the last relatively to the knife, and also to support the insole out of contact with the last adjacent to the point of operation of the knife.

The bracket 2 is provided with another 90 guideway 20 within which is arranged a projection from an adjustable slide 22 which is provided with a clamp screw 13. The slide 22 carries an angularly arranged gage 24 which is adapted to support the bottom 95 face of the heel seat portion of the insole on the last, and to co-operate with the gage 5 in positioning the last relatively to the knife. A bracket 25 is affixed to the gage 24 and supports a sliding bolt 26 which is provided 100 with a yoke 27 carrying a pin upon which turns a roller 28. A spring 29 surrounds the bolt 26, is confined between the bracket 25 and the yoke, and acts to press the roller through an aperture 10 in the gage 24 and 105 against the face of the insole, to press and hold the latter in engagement with the last. The outer end portion of the bolt 26 is provided with suitable lock and stop nuts 30 for limiting the extent of the inward movement 110 of the roller.

In the use of the machine, power will be applied through the belt 8 to rotate the knife 6 at a suitable speed. An insole 15 having been fastened temporarily to the bottom of a last, the last and insole are presented to the machine with the toe pointing up and the heel breast portion of the insole located between the tongue 9 and the face of the gage 24. The projecting marginal portion of the insole will thus be braced beyond the edge of the heel seat portion of the last, and the gage 5 will hold the last out of engagement with the knife and will so position the last relatively to the knife as to determine the line along which the insole will be trimmed. The bottom face of the insole will be held firmly against the spring-pressed roll 28 which will press the insole against the last and hold it in position dur- 115 120 125 130

ing the trimming operation. The last will be manipulated by the operator so as to trim progressively along the edge of the insole about the heel seat, and the insole will be 5 trimmed accurately to the contour of the last around the entire heel seat portion thereof. The work-engaging face of gage 24 is tangential to an arc rather than radial to the axis of the knife, and the trimmed edge 10 will be beveled accordingly.

The sole-rest 24 and tongue 9 thus cooperate in guiding the insole relatively to the knife and the gage 5 and tongue 9 cooperate in guiding the last.

15 The tacks that are used to secure the insole to the last may be located in the shank and forepart, the roller 28 being sufficient to prevent the heel seat portion of the insole from slipping edgewise relatively to 20 the last, without requiring a tack in the heel seat. This has the advantage that no tack comes into contact with the plate 24 on the roller.

The trimming knife is such that it cannot 25 enter and leave the work so abruptly as to form shoulders on the sole, being in this respect a more desirable knife than those of the chopping type heretofore used for this operation.

30 Having thus described my invention, what I claim as new and desire to secure by Letters Patent of the United States is:

1. A machine for trimming the heel-seat margin of an insole attached to a last, comprising 35 a rotary knife having an endless annular cutting edge directed to cut substantially at right angles to the direction of movement of its edge, and means arranged to engage the last and the marginal portion of the insole so as to guide them in a direction substantially at right angles to said cutting edge.

2. A machine for trimming the heel-seat margin of an insole attached to a last, comprising 45 a knife having an endless cutting edge directed to cut substantially at right angles to the direction of movement of its edge, and means arranged to engage the last and the marginal portion of the insole so as to guide them in a direction substantially at right angles to said cutting edge.

3. In a machine for trimming an insole attached to a last, the combination with confronting sole-engaging abutments arranged 55 to form a channel for the marginal portion of the sole and to engage the opposite faces of said margin to brace it against

flexure, of a rotary trimming knife having an annular cutting edge arranged to extend transversely of said channel so as to cut 60 in one direction regardless of the direction in which the knife is rotated.

4. In a machine for trimming an insole attached to a last, a rotary annular knife, a work-rest having a face arranged to engage the heel seat portion of the insole, and a spring-pressed roll arranged to roll on 65 said heel seat portion to keep the latter against the last.

5. In a machine for trimming an insole 70 attached to a last, a rotary annular knife, means for engaging the side of the last to position the latter relatively to the knife, a work rest arranged to engage the heel seat portion of the insole, and a spring-pressed 75 roll arranged to press the insole against the last.

6. In a machine for trimming an insole attached to a last, a rotary annular knife, means for positioning the work relatively 80 to said knife comprising a sole-rest arranged to engage the heel seat portion of the insole, said sole-rest having an opening, a spring-pressed roll arranged to occupy said opening to hold said insole in engagement 85 with the last, and means arranged to engage the side of the last to position the work relatively to the knife.

7. In a machine for trimming an insole attached to a last, a rotary annular knife, 90 means for positioning the last relatively to the knife including a device to extend between the last bottom and the insole, said means being adjustable toward and from the axis of the knife, an adjustable sole- 95 rest arranged to position the sole with its heel seat face parallel to the axis of said knife, and an anti-friction roller arranged to bear on the insole to sustain the drag of the knife.

100 8. A machine for trimming a last-supported insole, comprising, in combination, a rotary annular knife, means arranged to engage the side of the last to guide the latter relatively to the knife, said means being 105 adjustable toward and from the axis of the knife, and an anti-friction roller arranged to bear on the heel seat face of the insole to sustain the latter against movement with the knife, said roller being adjustable relatively to said last-guiding means.

In testimony whereof I have signed my name to this specification.

THOMAS LUND.
